UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

GUN-CARRIAGE.

1,321,774.

Specification of Letters Patent.

Patented Nov. 11, 1919.

Application filed July 30, 1917. Serial No. 183,594.

To all whom it may concern:

Be it known that I, EUGÈNE SCHNEIDER, a citizen of the French Republic, residing at Le Creuzot, Saône-et-Loire, France, have invented a new and useful Improvement in or Relating to Gun-Carriages, which is fully set forth in the following specification.

This invention has for its object to provide an improved carriage for guns of large 10 caliber.

This improved gun carriage comprises a carriage framing of the platform type, the central portion of which is adapted to carry the gun mounting proper, while the ends 15 of the carriage framing are supported on or suspended from the truck of two pairs of caterpillars.

According to the present invention the supporting on or suspension from the caterpillar trucks is effected by a member of inverted T-shape whose base or horizontal cross piece rests at its ends by means of bearings upon the corresponding two caterpillar trucks, and constitutes the pivot for 20 the rocking movement of each of the said caterpillars. The vertical limb of this T-shaped member is pivoted on the said base and serves at its upper part as a kind of attachment for the corresponding end of the 25 carriage framing. This attachment may be rigid, but is preferably constituted by means of shock-absorbers of the spring, hydraulic or other type. The base or cross-piece of the connecting T-shaped member 30 between the carriage framing and the pair of caterpillars may be so constructed as to serve for the attachment thereto of a draft-device. The vertical limb of the connecting T-shaped member may either serve exclusively 35 for the attachment to or suspension from the end of the carriage framing, or it may serve also as a vertical pivot pin for enabling the corresponding two caterpillars to be steered or rotated horizontally as a 40 whole relatively to the carriage framing.

The manner in which this invention is to be performed will now be more particularly described with reference to the accompanying drawings which illustrate by way of 45 example two constructional forms of an improved gun carriage according to the present invention.

In these drawings:

Figures 1-7 illustrate a constructional 50 form of an improved gun carriage accord-

ing to the present invention and Figs. 8 to 12 illustrate a second constructional form of an improved gun carriage according to the present invention, which is characterized by devices to allow of firing the gun when the 60 gun carriage as a whole, including the supporting caterpillars, has been brought parallel to the covering parapet.

Fig. 1 is a side elevation of the general arrangement of the improved gun carriage; 65

Fig. 2 is a plan of the same,

Fig. 3 is a side elevation partly in vertical section on the line III—III of Fig. 2, drawn to a larger scale.

Figs. 4 and 5 are vertical longitudinal 70 sections respectively on the lines IV—IV and V—V of Fig. 6;

Fig. 6 is a vertical cross section on the line VI—VI of Figs. 4 and 5;

Fig. 7 is a partial horizontal section on 75 the line VII—VII of Fig. 6;

Fig. 8 is a plan view showing the gun carriage brought into the position for firing parallel to the covering parapet;

Fig. 9 is a longitudinal side elevational 80 view of the gun carriage in position for transport;

Fig. 10 is a sectional elevation on the line III—III of Fig. 8;

Fig. 11 is a detail view on a larger scale 85 in sectional elevation on the line IV—IV of Fig. 8, of the elastic anchor and of the abutment of the folding strut upon the latter;

Fig. 12 is a partial cross-section on the line V—V of Fig. 8. 90

In all these figures, A is the central portion of the carriage framing on which the gun mounting proper B is removably mounted or fixed by any suitable means.

The forward end A¹ and the rear end A² 95 of the carriage framing, each rests on the two trucks C¹ C¹ and C² C² respectively of two pairs of caterpillars of known construction; these caterpillars serve solely as supporting members.

According to the present invention the ends of the carriage framing rest upon the pairs of caterpillars by means of a T-shaped member. The base, or horizontal cross-piece D of this T-shaped member is journaled in bearings e carried by the corresponding two caterpillar trucks (Fig. 6). 105

The vertical limb E of this T-shaped member serves for the attachment of the corresponding end of the carriage framing. 110

In the example shown, the attachment of the carriage framing is effected by means of shock-absorbers. For this purpose the vertical limb E of the T-shaped connecting member extends through the body of the carriage framing and carries a plate F on its upper end. This plate serves on one hand for the attachment of rods G supporting the lower abutment H for metal springs I, the upper abutment for which is constituted by the carriage framing (Fig. 6).

The plate F at the front end A¹ may and preferably does serve for the attachment to one element (for instance the piston J) of liquid shock-absorbers, the other element of which (for instance the cylinder K) is contained in the carriage framing (Fig. 3).

In the case of the forward end A¹ of the carriage framing, the T-shaped connecting member (which by means of the end journals of the cross-piece D, allows of an individual longitudinal rocking movement of each of the corresponding caterpillars about the axis of its end journal) is further so constructed as to allow of the two caterpillars as a whole being steered or rotated horizontally relatively to the end of the carriage framing. For this purpose the plate F which is supported by the upper end of the vertical limb E, may be adapted to turn by means of a footstep bearing on said limb instead of being rigidly fixed to the limb.

As shown in Fig. 3, the vertical limb E has a recess in which a pivot pin M is supported by means of Belleville washers L. The plate F engages this pivot pin by means of a sleeve f with an interposed steel block f¹.

As shown the vertical limb E may be extended below the cross-piece D, in the form of an extension E¹ engaging a collar N to which are attached the lower ends of tie-rods or struts O whose upper ends are fastened 45 to the underside of the carriage framing.

The connecting T-shaped member D—E for the rear end A² of the carriage framing is illustrated in Figs. 4 to 7.

In this construction the vertical limb E is pivoted by means of an eye e on a pin d extending through a slot in the cross-piece D. This construction allows a tilting movement of the two caterpillars as a whole in a transverse vertical plane about the pivot pin d, in addition to the individual longitudinal rocking movement of the two caterpillars about the axis of the cross-piece D.

All horizontal rotational movement of the rear caterpillars as a whole relatively 60 to the carriage framing is prevented by the guidance of the cross-piece D between two pairs of side members O¹ which serve also as ties and are attached at their upper ends to the underside of the carriage framing,

while their lower ends are attached to the 65 collar N.

The gun carriage is drawn preferably by means of a draft-pole such as shown in Figs. 1, 2 and 3, comprising a fork whose limbs P are attached to blocks on the cross-piece D. 70

In firing, the gun carriage is assumed to be resting on three supports, namely the support constituted by the front caterpillars as a whole and the two supports constituted by the two rear caterpillars which are capable of transverse movement about the pivot d. The strains due to firing are suitably taken by the shock-absorbers which also insure an elastic suspension of the carriage during transport. 75

During the firing the caterpillars may be prevented from rolling by a brake Q operated in the usual manner by means of a handwheel q situated within reach of the gun crew. 80

According to the invention illustrated in Figs. 8-12 auxiliary supports are provided each constituted by a folding strut, which is jointed at one end to the carriage framing and is supported at its other end elastically 90 by an anchor carrying a hydraulic or other brake combined with a recuperator.

This anchor is preferably constructed in such a manner as to form a brake for absorbing the vertical component of the force of 95 the recoil, and also to form an abutment for a vertical appendix carried by the rear end of the folding strut, for the purpose of effecting the absorption by the anchorage, of a considerable portion of the horizontal 100 component of the force of the recoil.

One of the folding struts is shown in full lines in Fig. 8, extended for use in the firing position of the gun, and in dot and dash lines folded away when the gun is in the 105 position for transport. The other strut is shown in dot and dash lines extended for use in the firing position of the gun, and in full lines folded away, in the position of transport. 110

In this example, the improved gun carriage comprises, as in the construction according to Figs. 1 to 7, a carriage framing A of the platform type that serves as a support at its middle portion for the gun mounting 115 proper B, with its forward end A¹ and rear end A² resting each on two trucks C¹—C¹ and C²—C² respectively of two pairs of supporting caterpillars.

For the purpose of being able to bring the 120 gun carriage into the firing position, parallel to the covering parapet D¹ (Fig. 10), the improved gun carriage is provided according to the present invention with two folding struts F¹—G¹ each jointed by its forward section F¹ to the platform carriage framing A—A¹, by means of a vertical hinge E² situated near the middle part A at an 125

equal distance from the transverse axis of the said carriage framing. The rear section G¹ of each strut is jointed to the section F¹ by means of a vertical hinge H¹ which allows 5 at will of folding the strut in position for transport or extending the strut for firing the gun. In their extended position the sections F¹ and G¹ are held in the prolongation of each other by a plug bolt I¹. The rear 10 end of the section G¹ rests elastically on the anchor placed on the ground.

This anchor comprises an anchor-plate J¹ provided with a spade K¹ which can be rigidly fixed to the anchor-plate or may consist of a stake engaged in a corresponding slot.

L¹ M¹ are two concentric sockets projecting from the anchor-plate J¹.

The socket M¹ forms a cylinder having 20 an axial counter rod m, for a hydraulic brake whose hollow piston N¹ forms part of the head O² upon which the strut section G¹ rests, through the medium of a screw g working in a corresponding screw-threaded 25 hole formed in the said section.

The inside face of the head O² forms a support for one of the ends of a recuperator spring P¹ whose other end bears against the bottom of the socket M¹. The outer 30 surface of the socket L¹ forms a supporting abutment for an appendix G¹¹ which is provided on the section G¹ of the folding strut near the rear end of the latter.

A suitable locking mechanism is provided 35 to maintain the folding strut F¹—G¹ in position for transport of the gun. In the example shown, an angle-plate Q² jointed by means of a hinge q² to a lug Q¹ projecting from the under edge of the longitudinal frame, is adapted to be turned down into the position shown in dot and dash lines in Fig. 12, for the purpose of extending the strut, or of being turned up into the position shown in full lines for holding the 40 folded strut; the horizontal limb of the angle plate engaging by means of a plug bolt q¹ the upper edge of the longitudinal frame.

Having now described my invention, what I claim as new and desire to secure by Letters Patent is:

1. In combination, a gun carriage frame of the platform type, a pair of caterpillar trucks at each end of said frame and inverted T-shaped members the cross pieces of 55 which have bearings on said trucks adapted to afford individual rocking movement for each truck, the stems of the T-shaped members constituting supports for said frame.

2. In combination, a gun carriage frame of the platform type, a pair of caterpillar trucks supporting the front and rear ends of said frame, inverted T-shaped members one of which comprises a horizontal cross-

piece having bearings on the forward trucks 65 to permit individual rocking movement of said trucks in the direction of travel, and a vertical stem yieldingly supporting said frame and turnable relatively thereto for steering, the other of said T-shaped members comprising a horizontal cross-piece having bearings on the rear trucks, and a non-revolute vertical stem yieldingly supporting said frame and having a pivotal support on its cross-piece to permit trans- 70 75 verse tilting of said rear trucks.

3. In combination, a gun carriage frame of the platform type, a pair of caterpillar trucks at each end of said frame, inverted T-shaped members having bearings on said 80 trucks adapted to afford individual rocking movement for each truck, the stem of each T-shaped member being provided with upper and lower abutment plates, said upper plate being fast to said frame and the lower 85 plate being slidable on said stem, shock-absorbing springs between said last-named plate and said frame, and other shock-absorbing means between said frame and said upper plate.

4. In combination, a gun carriage frame of the platform type, a pair of caterpillar trucks at each end of said frame, inverted T-shaped members having bearings on said 90 trucks adapted to afford individual rocking movement for each truck, the stems of said T-shaped members being provided with upper and lower abutment plates, the upper plates being fast to said frame and one of which is turnable on the end of its stem to 100 permit steering, said lower plates being slidable on said stems, shock-absorbing springs between said last-named plates and said frame, and other shock-absorbing means between said frame and said upper plates. 105

5. In combination, a gun carriage frame of the platform type, a pair of caterpillar trucks at each end of said frame, and inverted T-shaped members the cross pieces of which have bearings on said trucks adapted to afford individual rocking movement for each truck, the stems of said T-shaped members constituting supports for said frame, one of said stems having a pivot connection with its cross piece whereby the latter with the trucks may tilt in respect to the carriage frame.

6. In combination, a gun carriage frame of the platform type, a pair of caterpillar trucks at each end of said frame, inverted T-shaped members the cross pieces of which have bearings on said trucks adapted to afford individual rocking movement for each truck, the stems of said T-shaped members constituting supports for said frame, one 115 of said stems having a pivot connection with its cross piece whereby the latter with the trucks may tilt in respect to the carriage 120 125

frame, and guide struts for one of said cross pieces fast to said frame and having a collar for receiving an extension of the stem of a T-member, said struts being adapted to prevent horizontal turning of said trucks relative to the carriage frame.

7. In combination, a gun carriage frame of the platform type, struts each having a member hinged at one end to the side of 10 said frame and provided at its opposite end with an extension hinged thereto, and ground anchors each including a shock absorber adapted to receive the end of an extension, said members being adapted to fold 15 against the side of the carriage frame for transportation.

8. In combination, a gun carriage frame of the platform type, struts each having a member hinged at one end to the side of 20 said frame and provided at its opposite end with an extension hinged thereto, and ground anchors each including a brake cylinder and piston, one of said elements being adapted to receive the end of one of said 25 extensions, said strut members being adapted to fold against the side of said carriage frame for transportation.

9. In combination, a gun carriage frame of the platform type, struts each having a

member hinged at one end to the side of 30 said frame and provided at its opposite end with an extension terminating in a thrust plate, ground anchors each having a yielding portion adapted to receive the vertical thrust component of said strut, and a rigid 35 portion adapted to receive the horizontal thrust component of said strut through said thrust plate.

10. In combination, a gun carriage frame of the platform type, struts each having a 40 member hinged at one end to the side of said frame and provided at its opposite end with an extension hinged thereto, and ground anchors each including a brake cylinder and piston yieldingly separated from 45 each other, one of said elements being adapted to receive the end of said extension, said thrust members being adapted to fold against the side of said carriage frame for transportation. 50

In testimony whereof I have signed this specification in the presence of two subscribing witnesses.

EUGÈNE SCHNEIDER.
